CLAIM

The ornamental design for a hay rake tine, as shown and described.

DESCRIPTION

FIG. 1 is a top perspective view of a hay rake tine; FIG. 2 is a front elevation view of a hay rake tine; FIG. 3 is a rear elevation view of a hay rake tine; FIG. 4 is a side elevation view of a hay rake tine; FIG. 5 is an opposite side elevation view of a hay rake tine; FIG. 6 is a top elevation view of a hay rake tine; FIG. 7 is a bottom elevation view of a hay rake tine; and, FIG. 8 is a side elevation view with a partial side elevation cut-away view of a hay rake tine received in a mounting clip. The broken lines showing portions of the design in all figures is included for the purpose of illustrating environment, unclaimed features, additional articles, and forms not part of the claimed design.
